UNITED STATES PATENT OFFICE.

LINDEN E. EDGAR, OF PHILADELPHIA, PENNSYLVANIA, ASSIGNOR TO
THE LINK BELT ENGINEERING COMPANY, OF PHILADELPHIA, PENN
SYLVANIA, A CORPORATION OF PENNSYLVANIA.

PLATE COOLING AND CONVEYING APPARATUS.

No. 823,400.

Specification of Letters Patent.

Patented June 12, 1908.

Application filed January 18, 1904. Serial No. 189,548.

To all whom it may concern:

Be it known that I, LINDEN E. EDGAR, a citizen of the United States, residing in Philadelphia, Pennsylvania, have invented certain 5 Improvements in Plate Cooling and Conveying Apparatus, of which the following is a specification.

The object of my invention is to cool and dry heated plates of any description while 10 being conveyed from one point to another.

My invention is especially adapted for use in connection with stereotype-plates used for printing purposes—such, for instance, as the curved plates made on an autoplâte or other 15 casting-machine; but it will be understood that my invention may be applied to the cooling of other plates without departing from my invention.

In the accompanying drawings, Figure 1 is 20 a side view of my improved apparatus, showing the parts in diagram. Fig. 2 is a sectional view on the line 2 2, Fig. 3; and Fig. 3 is a sectional view on the line 3 3, Fig. 2.

Heretofore stereotype-plates were cooled 25 by hand-dipping, after which they were allowed to stand and drain until dry. By my invention I am enabled to thoroughly cool the plates and then completely dry them while they are traveling from one point in a 30 printing-office to another.

Referring now to the drawings, A is an endless conveyer made up of two sets of chains a a, tied together by rods a' a''. The conveyer passes around wheels on the driving-shaft b, around guides at b', and into a tank D. In the tank are guide-rollers b² b³, under which the conveyer passes, so that the plates carried by the chain will be submerged 35 in the liquid in the tank and cooled. At the opposite end of the tank the conveyer passes over a suitable guide at b³, then around a foot-wheel b⁴. The return run of the chain can be guided in any suitable manner. Fingers c at the foot-wheel remove the plates 40 from the conveyer.

In order to properly support the plates x, which are oblong and curved in cross-section in the present instance, I provide carrying-frames E, which are spaced at suitable 45 distances apart. These carrying-frames E are pivoted to one cross-bar a' of the chain, as shown in Fig. 2, and are preferably slotted at e for the free passage of the cross-bar a'', so

that the chain can have freedom in passing around guide-wheels or curved guides. The 55 frame in the present instance consists of two side members e', each having a bearing on the shaft a', and these side members are connected together by a curved member e'', which preferably conforms to the shape of 60 the plate. Flanges e² are formed at each edge to hold the plate in a fixed position while being transferred, cooled, and dried.

Mounted at the delivery end of the trough D is an air-pipe F, having suitable perforations, so that when the plates leave the tank 65 the air will blow the water from the plates and quickly dry them. While I have shown only one air-blast pipe, there may be more than one, if desired. I preferably control 70 the delivery of air from this pipe so that it will only deliver while the plate is in line with it, and thus not unnecessarily waste the air.

Different devices may be designed to automatically control the air, the device shown in the drawings consisting of a star-wheel f, mounted on a valve-stem f', the arms of the star-wheel being in the path of the cross-bars a' a''. The stem f' carries a valve mounted 75 in the valve-casing F', which controls the flow of air through the pipe F. This pipe has a series of perforations to allow for the escape of air. As the conveyer A travels, the cross-bars a' and a'' strike the teeth of the 80 star-wheel f and turn the air-valve F' on and off, so that air only escapes from the pipe F during the time the plate x is passing under it.

The operation is as follows: For instance, 85 if the plates to be cooled are plates for printing newspapers then the conveyer extends from the casting-room to the press-room, and the tank is suitably situated between the two points. The operator simply places the plate 90 as it is removed from the casting-machine onto a carrier E at the receiving end, and as the conveyer travels the plate is carried through the water in the tank D, and as it emerges from the tank it is subjected to the 95 blast of air, so as to quickly remove the water adhering to the plate. By the time the plate reaches the press-room it is completely dried and ready to be mounted in position.

I claim as my invention—

1. The combination of an endless conveyer,

a tank through which the carrying-run of the conveyer passes, an air-blast pipe at the delivery end of the tank, means for automatically controlling the flow of air through the pipe so that a plate carried by the conveyer will pass through the tank and be cooled and then subjected to a blast of air which is allowed to escape from the pipe while the plate is crossing its path, substantially as described.

2. The combination of an endless conveyer, plate-carriers mounted on the said conveyer, a tank through which the carrier on the chain passes, an air-blast pipe at the delivery end of the tank, and a valve for controlling the flow of air through the pipe, said valve being operated by the conveyer, substantially as described.

3. The combination in an endless conveyer,

of two chains, transverse rods connecting the chains, a plate-carrying frame pivoted to one of the cross-bars of the chain and slotted for the free passage of another cross-bar so that the chain can have freedom in passing around guides, the said frame being curved for the reception of the plate and flanged at each edge to hold the plate in a fixed position, and a tank, with means for directing the conveyer through the tank, substantially as described.

In testimony whereof I have signed my name to this specification in the presence of two subscribing witnesses.

LINDEN E. EDGAR.
